(57) **CLAIM**

We claim the ornamental design for a sleeve container, as substantially shown and described.

DESCRIPTION

FIG. 1 is a front side perspective view of a sleeve container. FIG. 2 is a rear side perspective view of the sleeve container shown in FIG. 1.

FIG. 3 is a front view of the sleeve container shown in FIG. 1.

FIG. 4 is a left side view of the sleeve container shown in FIG. 1.

FIG. 5 is a right side view of the sleeve container shown in FIG. 1.

FIG. 6 is a rear view of the sleeve container shown in FIG. 1.

FIG. 7 is a top view of the sleeve container shown in FIG. 1; and,

FIG. 8 is a bottom view of the sleeve container shown in FIG. 1.

The broken lines in the drawings depict portions of the sleeve container that form no part of the claimed design. The dotted lines in FIG. 8 depict the boundaries of the claim and form no part thereof.
